UNITED STATES PATENT OFFICE.

WALTER J. BELL, OF LOS ANGELES, CALIFORNIA, ASSIGNOR, BY DIRECT AND MESNE ASSIGNMENTS, TO LOS ANGELES SWITCH AND SIGNAL COMPANY, OF LOS ANGELES, CALIFORNIA, A CORPORATION.

POWER-APPLYING APPARATUS FOR OPERATING SWITCHES, SIGNALS, AND OTHER DEVICES.

No. 897,516.

Specification of Letters Patent.

Patented Sept. 1, 1908.

Application filed August 7, 1905. Serial No. 272,964.

To all whom it may concern:

Be it known that I, WALTER J. BELL, a citizen of the United States, residing at Los Angeles, in the county of Los Angeles and State of California, have invented a new and useful Power-Applying Apparatus for Operating Switches, Signals, and other Devices, of which the following is a specification.

This invention is applicable to many uses, but is more particularly designed for use in cases where power is applied through pneumatic means.

An object of the invention is economy of air and power, and provision of means whereby the application of air to operate switches, signals, and other devices may be made more direct than heretofore.

In this invention the space between the air valve and the cylinder, or other device through which the power of the compressed air is applied, is reduced to a minimum.

This invention embraces liquid means for the control of the pneumatic means; that is to say, I have provided in this power apparatus liquid means by which the pneumatic means for transmitting and applying the power is controlled, and this newly invented apparatus comprises pneumatic means and liquid means for controlling the same. The pneumatic means may comprise apparatus operated by compressed air or by suction or vacuum, and the liquid means may also be under pressure or suction.

The invention also embraces a specific construction of valve means by which the liquid of the liquid means is appropriately directed, and the same valve is also applicable for giving the appropriate direction to the air of the pneumatic means. The means for causing pressure or exhaust for the liquid means and also for the pneumatic means may be of any well-known kind.

In the application of this invention for the operation of switches or signals, a lever may be provided for operating the liquid means, and said lever may be actuated manually, magnetically, or otherwise, as may be deemed desirable or expedient.

A principle of this invention is that a valve for controlling the pneumatic means by admitting air from the supply pipe to the engine from which the power is applied, is located close to such engine, and in turn is operated

by an engine through a liquid means which may be located at a great distance from the engine through which the power is applied. It is to be understood, however, that the mechanism of the system hereinafter described is applicable for use with a liquid medium for operating both engines, and that it also may be used with pneumatic medium for operating both engines, and that a variation in the character of pressure medium will not avoid my invention relative to such mechanism.

The fluid power-transmitting medium may be air, water, oil, alcohol, or any other convenient fluid that will serve the work in hand. In some instances, the engine from which the power is to be applied for moving a switch point or for other service, may be operated by vacuum controlled by another engine operated by vacuum means, or either of such engines may be operated by pressure and the other by vacuum means; or either engine may be operated by liquid medium under pressure, or suction, and the other engine by pneumatic medium under pressure or vacuum.

The various adaptations of the medium and the means thus suggested will be understood from the following detailed description.

The accompanying drawings illustrate the invention in two modes of its application. Figure 1 is a fragmental view partly in section, showing a system or apparatus embodying this invention in a form applicable for operating a switch from a considerable distance. Fig. 2 is a plan of a valve chest with the top removed. Fig. 3 is a side elevation of such chest. Fig. 4 is a fragmental, sectional elevation illustrating the application of the invention as applied for operating a switch close by.

The pneumatic means comprises in a general way, air supply and exhaust pipes 1, 2; a power-applying device or engine 3; air supply and exhaust pipes 4, 5; valve means 6 for controlling the passage of the air for operating the power-applying device 3. The liquid means for controlling the pneumatic means, in a general way, comprises supply and exhaust pipes 7, 8, respectively; pneumatic-valve controlling device or engine 9 suitably connected as by piston rod 10 to

- operate the pneumatic valve means; pressure and exhaust pipes 11 and 12 for applying pressure to operate the pneumatic-valve controlling device; valve means 13 for controlling the passage of the pressure medium 14 for operating the pneumatic-valve controlling device 9, and means 15 for operating the valve which controls the passage of the pressure medium.
- 16 designates a pressure or exhaust pump for the pneumatic means, and 17 a pressure or exhaust pump for the liquid means. 18 and 19 are receivers or tanks for said pumps, respectively.
- 20 is the cylinder of the pneumatic power-applying device or engine 3; 21 is the piston, and 22 the piston rod therefor, ports 23, 24, being in said cylinder, one on each side of the piston, each of said ports being both for supply and exhaust.
- 25 is a valve chest provided with air supply and exhaust ports 26, 27, and connected with pipes 4 and 5.
- 28 designates valves in the valve chest for controlling the air for said ports; said valves are reversely arranged. The valve chest 25 is composed of two chambers 29 and 30.
- 31 is a way communicating between the chambers 29 and 30, and connected with the pressure pipe 1. 32 is a way between said chambers and communicating with the exhaust pipe 2.
- 33 is an internal valve for simultaneously opening the way into one chamber and closing that into the other chamber, and vice versa.
- 34 is an external valve for simultaneously opening the passage between way 32 and one chamber, and closing the passage between said way and the other chamber, and vice versa. 35 is a beam pivotally connected with said valves for operating the same, and also pivotally connected with the piston rod 10 whereby the beam is operated for working the valves. The valves are provided with guides *a* for holding them true.
- 36 is a cylinder, and 37 a piston therein for operating the rod 10, ports 38, 39, being provided communicating with the pipes 11 and 12, respectively, and being on opposite sides of the piston 37.
- 40 is a valve chest having ports 41, 42, for pressure and exhaust.
- 43 indicates valves in the valve chest for controlling the pressure medium 14 and reversing its movement through pipes 11 and 12. Said valve chest has two chambers 44, 45, and ways 46, 47, between said chambers communicating through ports 41 and 42 with pressure and exhaust pipes 7, 8.
- 48 is an internal valve for simultaneously closing the passage between the way 46 and one of said chambers, and opening the passage between said way and the other of said chambers, and vice versa. 49 is an external

valve for simultaneously opening the passage between the way 47 and one of said chambers, and closing the passage between said way and the other of said chambers, and vice versa.

50 is a beam pivotally connected with the valve rods 51, 52, of valves 48, 49. 53 is a connecting rod connecting said beam with an arm 54 of rock shaft 55 controlled by lever 56.

The internal valves 33 and 48 are located within their respective ways and comprise two heads *b*, *c*, which engage internal valve seats *d*, *e* according as the valve may be shifted. The external valves 34 and 49, respectively, comprise two heads, *f*, *g*, arranged outside the ways 32 and 47, respectively, and seating on external seats *h*, *i*, respectively, in every case a valve seat being placed on each side of the way ports 26, 27, 41 and 42.

57, 57', are caps for the valve chests.

58, 58', are caps for the ways 31, 46, between the chambers; 59, 59', are plugs to give access to the exterior valves 34 and 49, respectively.

For disassembling and assembling the valve means for repair or otherwise, the caps 57, 57', may be removed, thus giving access to the valve chambers 29 and 44, whereupon the caps 58, 58', may be removed and the valves 33 and 48 taken out. To take out the external valves 34 and 49 it is necessary to remove the plugs 59, 59' whereupon the valve heads *g* may be unscrewed from the valve rods, *j*, 52, after which the external valves may be removed from their ways.

In practical operation, pressure or exhaust will be effected so that the pressure medium 14 will be forced from the inlet 7 toward outlet 8, and like pressure or exhaust will be exerted to force the pressure medium in the pneumatic means from the inlet 1 toward the outlet 2.

To operate the power-applying engine or device 3 the lever 56 will be moved manually or otherwise in an appropriate direction for closing the inlet passage 46 into one chamber, as 44, and opening said passage into the other chamber, as 45, and at the same time closing the exhaust passage 47 from chamber 45 and opening the exhaust passage 47 from the chamber 44, whereupon the pressure medium will operate through the pipe 12 to force piston 37 up, said pressure medium passing from the cylinder 36 through pipe 11 and out through passage 47 and exhaust pipe 8. By this operation power is transmitted through the incompressible liquid medium 14 which may be water, oil, alcohol, or any other liquid to drive the engine 9, operating the rod 10 and the valves 28 to close the inlet passage 31 into chamber 29 and open said passage 31 into chamber 30; at the same time opening the passage from chamber 29 into the exhaust passage 32 and closing the passage from chamber 30 to said exhaust

passage, whereupon the pressure medium will flow through pipe 5 to move the piston 21, the pressure medium in the cylinder 20 being expelled through pipe 4, passage 32 and exhaust pipe 2.

5 In the form shown in Fig. 4, 60 is a handle for operating a pump piston 61 which applies power through liquid medium 62 to operate the diaphragm 63 and through the rod 64, beam 65 to operate valves 67, 68, of the pneumatic means 6", whereupon the pressure medium operates as before described upon the power-applying device or engine to move the switch or other device to be operated.

10 15 It is to be understood from Fig. 4 that I contemplate using a diaphragm as the equivalent of a piston, and that the invention may be variously embodied without departing from the spirit thereof.

20 25 It is to be understood that in case of pneumatic means it is only necessary to connect either the supply or the exhaust with the pressure or the vacuum pump, as the case may be. In the drawings, however, a complete connection or circuit for the fluid medium is shown. Such parts of the same may be omitted as the constructor may find it desirable to dispense with.

What I claim is:—

30 35 1. A pneumatic engine, air-supplying means therefor, means for controlling the air for said engine, a liquid engine for controlling the air-controlling means, a pump adapted to supply liquid thereto, pipes connecting said pump with said engine, and means for reversing the flow of liquid through said pipes.

40 45 2. Two chambers, each having a port; ways between the chambers each having a port; reverse valves for opening and closing the passage between the way ports through one and the other chamber alternatively; a beam connected with said valves, and a rod connected with said beam for operating the same.

50 55 3. Two chambers, each having a port; ways between the chambers each having a port, said ways being respectively provided with external and internal valve seats each side of the way ports; reverse valves in said ways adapted to seat on said seats; and means for operating said valves.

60 65 4. A cylinder, a piston therein, ports being in said cylinder, one on each side of the piston; pipes, one for each port; a valve chest provided with air supply and exhaust ports and connected with said pipes; valves in the valve chest for controlling the air for said ports; another cylinder; a piston therein, ports being in said other cylinder, one on each side of the piston therein; pipes, one for each of the last-mentioned ports; a valve chest provided with supply and exhaust ports and connected with said last-mentioned pipes; means for supplying pressure

to said last-mentioned pipes alternatively through said valves, and means for controlling said valves.

5 10 15 20 25 30 35 40 45 50 55 60 65 70 75 80 85 90 95 100 105 110 115 120 125 130

5. Two chambers, each provided with a port; two ways between said chambers, each provided with a port; pressure means operating through said ports and ways, and reversing valves for opening and closing the passage between the way ports through one and the other chamber alternatively.

6. Two chambers, each provided with a port; two ways between said chambers, each provided with a port; pressure means operating through said ports and ways, reversing valves for opening and closing the passage between the way ports through one and the other chamber alternatively, a cylinder having ports connected with the chamber ports respectively, and a piston in the cylinder between the cylinder ports.

7. Two chambers, each provided with a port; two ways between said chambers, each provided with a port; pressure means operating through said ports and ways; reversing valves for opening and closing the passage between the way ports through one and the other chamber alternatively; a cylinder having ports connected with the chamber ports respectively; a piston in the cylinder between the cylinder ports; other two chambers, each provided with a port; two ways between said chambers, each provided with a port; pressure means operating through said ports and ways; reversing valves for opening and closing the passage between the last-named way ports through one and the last-named chambers alternatively; and means connecting said last-mentioned reversing valves with said piston for operating said valves simultaneously.

8. Two chambers, each provided with a port; two ways between said chambers, each provided with a port; pressure means operating through said ports and ways; reversing valves for opening and closing the passage between the way ports through one and the other chamber alternatively; a cylinder having ports connected with the chamber ports respectively; a piston in the cylinder between the cylinder ports; other two chambers, each provided with a port; two ways between said chambers, each provided with a port; pressure means operating through said ports and ways; reversing valves for opening and closing the passage between the last-named way ports through one and the other of the last-named chambers alternatively; means connecting the last-mentioned reversing valves with said piston for operating said valve simultaneously; another cylinder having ports connected respectively with the last-mentioned chamber ports, and a piston in the last-mentioned cylinder between the ports thereof.

9. Two chambers, each provided with a

- port; two ways between said chambers, each provided with a port; liquid pressure means operating through said ports and ways; reversing valves for opening and closing the 5 passage between the way ports through one and the other chamber alternatively; a cylinder having ports connected with the chamber ports respectively; a piston in the cylinder between the cylinder ports; other two 10 chambers, each provided with a port; two ways between said chambers, each provided with a port; pressure means operating through said ports and ways; reversing valves for opening and closing the passage 15 between the last-named way ports through one and the last-named chambers alternatively; means connecting said last-mentioned reversing valves with said piston for operating said valves simultaneously; another cylinder having ports connected respectively with the last-mentioned chamber ports, and a piston in the last-mentioned cylinder between the ports thereof. 20
10. Two chambers, each having a port; 25 ways between the chambers, each having a port; and reversing valve means for opening and closing the passage between the way ports through one and the other chamber alternatively.
30. 11. Two chambers, each having a port; two ways between the chambers, each having a port; an internal valve for one of the ways constructed and arranged for simultaneously opening the passage between such way and 35 one chamber, and closing that between such way and the other chamber, and vice versa; an external valve for the other way constructed and arranged for simultaneously closing the passage between its way and the one 40 chamber, and opening the passage between such way and the other chamber, and vice versa; and means for simultaneously operating the valves. 45
12. Two chambers, each having a port; ways between the chambers each having a port; reverse valves for opening and closing the passage between the way ports through one and the other chamber alternatively; a beam pivotally connected with said valves, 50 and a rod pivotally connected with said beam for operating the same.
13. Two chambers, each having a port; two ways between the chambers, each hav-
- ing a port; an internal valve for one of the ways constructed and arranged for simultaneously opening the passage between such way and one chamber, and closing that between such way and the other chamber, and vice versa; an external valve for the other way constructed and arranged for simultaneously closing the passage between its way and the one chamber, and opening the passage between such way and the other chamber, and vice versa; a beam pivotally connected with said valves; a rock shaft pivotally connected with said beam, and means for operating the rock shaft. 55
14. Two chambers, each provided with a port; ways between said chambers, each provided with a port; liquid means in said chambers, ports and ways; reversing valves for opening and closing the passage between the way ports through one and the other chamber alternatively; an engine connected with the chamber ports to be operated by said 70 liquid medium; a pneumatic pressure medium; an engine to be operated by said pneumatic pressure medium, and valve means operated by said first-mentioned engine for controlling said pneumatic pressure medium. 75
15. An engine; two chambers, each having a port, said ports being connected with the engine; ways between the chambers, each having a port; a power-transmitting medium in said engine, chambers, ways, and 80 ports; and reversing valves for said ways for closing the passage between one chamber and one way, and opening the passage between said chamber and the other way, and at the same time opening the passage between the other chamber and the one way and closing the passage between said other chamber and the said other way. 85
16. The combination of a regulable pneumatic engine, liquid-operated means for controlling the same, and flow-reversing means for controlling the liquid for the liquid-operated means. 90

In testimony whereof, I have hereunto set my hand at Los Angeles, California, this 2d day of August 1905.

WALTER J. BELL.
